DESIGN FOR A TOWEL OR SIMILAR ARTICLE

Max Klein, New York, N. Y., assignor to Mosse,
Incorporated, New York, N. Y.

Application July 11, 1936, Serial No. 63,793

Term of patent 7 years

To all whom it may concern:

Be it known that I, Max Klein, a citizen of the United States, residing at New York city, in the county and State of New York, have invented a new, original, and ornamental Design for a Towel, or Similar Article, of which the following is a specification, reference being had to the accompanying drawing forming a part thereof.

Fig. 2 is an elevational view, on an enlarged scale, in which portion A', B', C', D' corresponds to portion A, B, C, D, of Figure 1.

I claim:

The ornamental design for a towel or similar article, as shown and described.

In testimony whereof I have signed this specification.

MAX KLEIN.
